(57) **CLAIM**

The ornamental design for a soap dispenser collapsible bottle, as shown and described.

DESCRIPTION

FIG. 1 is a perspective view of a bottle embodying our new design;

FIG. 2 is a front view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawings showing the soap dispenser collapsible bottle illustrate the portions of the soap dispenser collapsible bottle that form no part of the claimed design.
